UNITED STATES PATENT OFFICE.

JOSEPH CONLEY, OF ANADARKO, OKLAHOMA.

LATRINE-INCINERATOR.

No. 928,100.

Specification of Letters Patent.

Patented June 29, 1909.

Application filed December 14, 1908. Serial No. 467,628.

To all whom it may concern:

Be it known that I, JOSEPH CONLEY, a citizen of the United States, residing at Anadarko, in the county of Caddo and State of Oklahoma, have invented certain new and useful Improvements in Latrine-Incinerators, of which the following is a specification.

My invention relates to certain new and useful improvements in latrine incinerators, and the object of my invention is to improve their construction and arrangement so as to provide an apparatus of this character which will be simple in construction, cheap to manufacture and effective in operation.

Another object of my invention is to produce an apparatus which may be readily transported from place to place and quickly set up and made ready for use.

With these and other objects in view my invention consists in certain constructions, combinations and arrangements of parts the preferred form of which will be first described in connection with the accompanying drawings and then the invention particularly pointed out in the appended claims.

Referring to the drawings wherein the same part is designated by the same reference numeral wherever it occurs, Figure 1 is a longitudinal vertical section on line 1-1 of Fig. 2; Fig. 2 is a top plan view; Fig. 3 is a vertical transverse section taken on line 3-3 of Fig. 1, and Fig. 4 is a longitudinal horizontal section taken on line 4, 4 of Fig. 1.

1 designates a box or casing preferably formed of sheet metal and of rectangular form.

2 is a box or casing extending up from the casing 1, the box extending across one end of the casing 1 and longitudinally thereof for approximately half the length thereof, though the length of the casing 2 in relation to the casing 1 may be varied as may be found most desirable. The casing 2 has no bottom and is therefore in communication with the casing 1. At the other end of the casing 1 is a tank 3, said tank being provided with a reticulated cover 4 through which liquid matter may pass into the tank.

5 designates the cover of the casing 2, and the said cover is provided with seat openings 6 having lids 7 hinged thereto.

8 designates screens mounted on top of the cover 5, said screens being so arranged as to

partition off the cover 5 into sections, each one of which contains a seat opening.

9 designates spring plates secured to the sides of the longitudinal screen sections, said springs tending to close the lids 7.

10, 10 are a pair of pans or containers extending longitudinally of the casing 2 from end to end thereof with each pan extending under a pair of seat openings 6. These pans are pivoted at their ends in the sides of the casing in any desired manner, the construction of the pans and the particular means for pivoting them as shown in this application being the same as that fully described and illustrated in my Patent No. 905,590, granted to me December 1, 1908.

11 are a series of pans located below the pans 10, each of said pans extending transversely of the casing 1 with its ends pivoted in the sides of the casing and the series of 15 pans extending the full length of the casing, the construction of pans and the means for mounting them being shown as identical with that described in my patent above referred to. Below the pans 11 are located the grate bars 12, said grate bars extending substantially the length of the casing 1.

13 is an ash pit formed in the bottom of the casing.

14 is a door opening through the front end of the casing over the grate bars through which fuel may be supplied to the whole length of the grate bars.

15 is a door opening over the grate bars and located in the side of the casing at the rear end thereof.

16 designates a stack provided in its lower portion with the grate bars 17 and a door 18 opening over the grate bars and an ash pit 19 located below the grate bars.

20 designates a flue extending from the end of the section 1 to the side of the stack 16. This flue is so located as to open into the casing and stack just over the grate bars 12 and 17. In this flue 20 I mount a damper 21 by means of which the passage of the products of combustion therethrough may be regulated. 22 designates a second flue extending from the rear end of the casing 1 into the side of the stack 16. This flue 22 is located above the flue 20 and opens into the casing just over the top of the series of pans 11, and the flue is provided with a damper 23.

24 designates a pair of curved pipe

connecting the upper and lower portions of the casing 1 at its front end, the lower end of the flue 24 opening into the casing below the pans 11, while its upper end opens into the casing above the pans 11.

25 are a pair of flues extending from the sides of the casing 2 around the sides of the casing 1 and opening into the sides of the flue 22. These flues 25 are also provided 10 with dampers 26.

27 is a pan supported on the bottom of the tank 3 by means of the supporting bars 28.

29 is a valved spout leading from the lower portion of the bottom of the tank 3 15 around the bottom of the tank 3 with its open end located so as to deliver the contents of the tank when the valve in the pipe is open, into the tank 27.

30 is a pipe having a valve 31 and having 20 its outer end formed into a pair of delivery spouts 32, the spouts 32 and the pipe 30 forming a Y. These spouts pass through the rear of the casing 2 with the spouts 32 extending just over the adjoining ends of 25 the pans 3, one of said spouts being in position to deliver into one pan and the other into the other.

33 are a pair of inclined troughs which extend the length of the casing 1, said 30 troughs being closed at their upper portion and being provided with a series of spouts 34 which extend in over the pivots of the pans 11 so as to empty into the pans.

35 are a pair of pipes which extend from 35 the sides of the tank 3 into the troughs 33, each being provided with a valve 36 to control the flow of liquid therethrough.

Because of the combined height of the casings 1 and 2 I provide steps 37 and also 40 foot boards 38 upon the sides of the casing 1, these steps and foot boards being secured to the side of the casing 1 in any desired manner, as by means of the supporting bars 39 for the steps 37 and the brackets 40 for the 45 foot boards 38.

In the operation of my apparatus a fire is built upon the grate 17, the damper 21 in the flue 20 and the damper 23 in the flue 22 being closed, while the dampers 26 in the 50 flues 25 are open. When there is an accumulation in the tank 3 and the pans 10, the wooden lids 7 are removed and a series of iron lids 42 are placed in position to cover the openings 6. A fire is now built upon the grate bars 12 and the dampers 23 opened. This causes the products of combustion to pass up through the flues 24 over the top of the pans 11 and beneath the pans 10. When the matter in the pans 10 has been dried 55 they are dumped into the pans 11 below them by turning the same over and the pans are preferably left in their inverted position, so that the products of combustion will have direct access to the interior of the pans to 60 thoroughly clean them. The matter now

contained in the pans 11 is subjected to a higher heat, and when it has been thoroughly dried out and burned the pans 11 are turned over and what is left is dumped onto the fire in the grate bars 12 where it is consumed. The liquid matter contained in the tank 3 may be permitted to pass into the pans 10 to be evaporated by opening the valve 31, and a portion of it may be drawn into the pan 27 by means of the valve 29, while another portion can be run into the pans 11 by means of the valves 36. The liquid matter can thus be distributed into the various pans and rapidly evaporated. After the incinerating operation is completed the fire may 80 be pushed back on the grate bars and a small quantity of it allowed to remain on the grate bars in front of the door 13. The pans are turned to their normal position, the damper 20 opened to permit the products of combustion to pass directly into the stack and then as soon as the apparatus has cooled sufficiently it is again ready for use.

I realize that considerable variation is possible in the details of construction and arrangement of parts without departing from the spirit of my invention, and I therefore do not intend to limit myself to the specific form shown and described.

I claim:

1. In a latrine incinerator, the combination with a casing provided with grate bars in its lower portion, a series of pans pivoted in the sides of the casing, said series extending the length of the casing and located over the grate bars, a second casing supported above the first mentioned casing at one end thereof, said last mentioned casing having a cover with seat openings therein, pans pivoted in said last mentioned casing and located beneath the seat openings, a stack outside said casing and a pair of flues provided with dampers connecting the first mentioned casing and the stack, the flues extending from the casing on opposite sides of the series of pans in the first mentioned casing.

2. In a latrine incinerator, the combination with a casing, of two series of pans mounted in the casing and dividing the incinerator longitudinally into three chambers, a grate located below the lower series of pans, a stack, and a flue extending from each chamber to connect each chamber with the stack.

3. In a latrine incinerator, the combination with a casing, of two series of pans mounted in the casing and dividing the incinerator longitudinally into three chambers, a grate located below the lower series of pans, a stack, a flue extending from each chamber to connect each chamber with the stack, a tank supported on the incinerator and valved pipes leading from said tank to each of the pans of each series.

4. In a latrine incinerator, the combina-

tion with a casing, of two series of pans mounted therein and dividing the incinerator longitudinally into three chambers, a tank supported on the incinerator, valved pipes leading from said tank to each of the pans of each series, a stack, and a flue connecting the casing with the stack.

5. In a latrine incinerator, the combination with a casing provided with grate bars in its lower portion, a series of pans pivoted in the sides of the casing, said series extending the length of the casing and located over the grate bars, a second casing supported above the first mentioned casing at one end thereof, said last mentioned casing having a cover with seat openings therein, pans pivoted in said last mentioned casing and located beneath the seat openings, a tank supported on said first mentioned cas-

ing, adjacent said second mentioned casing, 20 said tank having a reticulated cover, valved pipes connecting said tank with said pans, a stack, and a flue connecting the casing with the stack.

6. In a latrine incinerator, the combination with a casing, of two series of pans mounted therein and dividing the casing longitudinally into three chambers, a stack, 25 a flue connecting each chamber with the stack, a fuel support in the bottom of the 30 casing and a flue connecting the lower chamber with the adjacent one.

In testimony whereof I affix my signature in presence of two witnesses.

JOSEPH CONLEY.
